CLAIM

The ornamental design for an inflatable physical therapy pillow, as shown and described.

DESCRIPTION

FIG. 1—Top, front, right side, perspective view of an inflatable physical therapy pillow.

FIG. 2—Bottom, front, left side, perspective view thereof.

FIG. 3—Front elevation view thereof.

FIG. 4—Rear elevation view thereof.

FIG. 5—Left-side elevation view thereof.

FIG. 6—Right-side elevation view thereof.

FIG. 7—Top plan view thereof; and,

FIG. 8—Bottom plan view thereof.

The claim is directed to an inflatable physical therapy pillow having a set of valves on one side.
